U.S. Cl. D15—8

FIG. 3

FIG. 4

FIG. 1 is a front perspective view of a chair showing our new design;

FIG. 2 is a rear perspective view of the same;

FIG. 3 is a rear perspective view taken from the side opposite that shown in FIG. 2, and

FIG. 4 is a front perspective view taken from the side opposite that shown in FIG. 2.

The patterned top of the seat cushion is essentially the same in appearance as the front of the back rest cushion.

This application is a continuation-in-part of our earlier filed copending case Serial No. D-16,840, filed Apr. 21, 1969 and now abandoned.

We claim:

The ornamental design for a chair, as shown and described.
